UNITED STATES PATENT OFFICE

JAMES S. SMITH, OF FORT WAYNE, INDIANA.

HORSE-DETACHER.

SPECIFICATION forming part of Letters Patent No. 232,082, dated September 7, 1880.

Application filed August 7, 1880. (Model.)

To all whom it may concern:

Be it known that I, JAMES SION SMITH, a citizen of the United States, residing at Fort Wayne, in the county of Allen and State of Indiana, have invented new and useful Improvements in Whiffletrees, of which the following is a specification.

This invention relates to a whiffletree so constructed that the horse may be instantly detached from the vehicle by the driver when desired.

In the accompanying drawings, Figure 1 is a top or plan view of my whiffletree with the upper plate, A, removed. Fig. 2 is a plan view of the central portion of the same complete. Fig. 3 is a side or edge view of said central portion. Fig. 4 is a cross-section on line *xx* of Fig. 2.

Figs. 2 and 3 are on a somewhat larger scale than Fig. 1, and Fig. 4 is on a still larger scale.

A and A' are two plates forming the central portion of the whiffletree and extending a little more than half its entire length.

B and B' are two swinging bars between the plates A A', and pivoted thereto at *a a'*, having at their outer ends hooks *b b'*, to which the traces are hitched. These hooks are so formed that when said bars swing round on their pivots the traces will automatically slip off and become released.

C is a hole for the king-bolt, which is surrounded by a rubber plate or ring, *c*. This rubber ring is of such size that when the arms B and B' are extended and locked in position their inner curved ends will press against its periphery, and its elasticity will keep said ends firmly pressed against the lugs or stops *d d'*, which hold them in position, and thus prevent any backlash and obviate noise.

D is a spring secured to the upper side of plate A, having two lugs or stops, *d d'*, projecting downward and passing through holes in said plate when said spring is pressed down upon it.

E is a lock for holding said spring D securely down upon the plate A, so that the lugs *d d'* will operate as stops to prevent the pivoted lever-arms B B' from turning, except when it is desired to detach the horse. This lock consists of a sliding bolt, F, a spiral

spring, *f*, to press the same forward over spring D, and hold the latter down upon plate A, and a flat spring, *f'*, at the rear end of said bolt F, which, by springing upward when the bolt is drawn back, prevents the bolt from being carried forward again by the spiral spring *f*. These locking devices are inclosed in a case secured to the upper side of plate A, as shown in Figs. 2 and 4.

A cord, *g*, is attached to the rear end of the lock-bolt F, the free end of which is carried back and through the bottom of the buggy, thence up over the dash-board, and down to the end of spring D, to which it is made fast.

When, in case of accident, or of the horse becoming unmanageable, it is desired to release him from the vehicle a pull upon the cord *g* will draw back the lock-bolt F, releasing the spring D, which will spring up so as to raise the lugs *d d'* from behind the curved ends of the lever-arms A A', and the latter will swing around on their pivots, so that the traces will slip off the hooks. If the elasticity of the spring D should fail to raise the lugs *d d'* sufficiently, a pull upon the cord *g* will secure that result.

The harness to be used with this invention must be so constructed that when the traces are detached the horse will freely pass from the shafts. To accomplish this, instead of fastening the holdback-straps to the shafts in the usual way, I fasten them to shaft-holders, and have bosses or lugs on the under sides of the shafts to prevent the latter from running through the holders, but leaving them free to slip out when the traces are detached.

I have shown and described my invention as adapted to a one-horse vehicle; but it is manifest that it is also applicable to a two-horse carriage, in which case the whiffletree will be attached to the double-tree.

I do not limit myself to the precise construction of the devices shown and described for locking the arms A A' in their extended position and releasing them therefrom, as other equivalent devices, operating in substantially the same manner to effect the same result, may be substituted without changing the essential principles of my invention.

What I claim as my invention is—

1. The plates A and A', the arms B and B', pivoted between them, the rubber ring *c*, the

spring D, with lugs or stops d d , and lock E, all constructed and combined to operate substantially as described.

2. The plates A and A', the arms B and B', pivoted between them, the spring D, with lugs d d , and the lock E, all constructed and combined to operate substantially as set forth.

3. In combination with the plates A A', the pivoted arms B B', and the spring D, with lugs d or stops d , the lock E, consisting of bolt F and

springs f f' , inclosed in a case, substantially as shown and described.

In testimony whereof I have hereunto set my hand and seal in the presence of two subscribing witnesses.

JAMES SION SMITH. [L. S.]
